UNITED STATES PATENT OFFICE

HUGO LEIPOLD, OF BUFFALO, NEW YORK, ASSIGNOR TO BUFFALO FIRE APPLIANCE CORPORATION, OF BUFFALO, NEW YORK, A CORPORATION OF NEW YORK

FIRE EXTINGUISHER

Application filed April 5, 1928. Serial No. 267,542.

This invention relates to a fire extinguisher and more particularly to an apparatus of this character of the portable type in which the tank is inverted for starting the operation of the extinguisher and playing the fluid on the fire.

As heretofore constructed it was possible for one of the liquids in the tank to discharge partly before becoming mixed with the other liquid so that the full efficiency of the apparatus was not obtained immediately upon inverting the tank.

It is the purpose of this invention to provide means for causing the two liquids in the tank to mix properly immediately upon inverting the apparatus and before any of the liquid escapes from the tank and thereby preventing any unmixed liquid from escaping from the tank and also increasing the rapidity and efficiency of the apparatus.

In the accompanying drawings:

Figure 1 is a vertical section of a fire extinguisher equipped with an approved form of my invention.

Figure 2 is a horizontal section taken on the correspondingly numbered line in Figure 1.

Figure 3 is a fragmentary inside view of the tank showing the baffle over the outlet of the tank.

In the following description the same reference characters indicate like parts in the several figures of the drawings.

The tank of the fire extinguisher is made of any suitable metal, as usual, and comprises a cylindrical body 10, a bottom 11, a semi-spherical dome or top 12 which is provided with a central inlet 13, and a cover 14 which closes said inlet and which is detachably connected with said dome. The interior of this tank forms an outer chamber 15 for one of the fluids 16 which is mixed with another liquid to produce the fire extinguisher solution or fluid whereby fires are quenched.

The dome of the tank is provided on one

side with a main outlet 9 for the mixed fire extinguishing solution or fluid and this outlet connects with a hose 17 having a delivery nozzle 18 for playing the extinguishing solution on the fire.

To prevent any large particles from escaping through the outlet a screen 19 is provided which is arranged within the dome and made of spherical form with its concave side facing outwardly and enclosing the main outlet and secured at its edge to the inner side of the dome.

Within the central part of the tank is arranged an upright tube 20 which forms an inner chamber 21 for the reception of the other liquid 22 which is adapted to be mixed with the liquid in the outer chamber and form therewith a fire extinguishing fluid. At its upper end the inner tube is provided with an inner outlet 23 which is arranged adjacent to the main outlet and which has a removable stopper 24 adapted to open upon inverting the apparatus and permit the liquid in the inner chamber to flow into the outer chamber and mix with the liquid in the latter for producing a fire extinguishing fluid.

In the absence of any provision to prevent it, some of the liquid from the outer chamber will escape through the outlet of the extinguisher before the same becomes mixed with the liquid in the inner chamber upon inverting the apparatus thereby reducing the efficiency of the apparatus and wasting material.

To avoid this a baffle 25 is provided which is constructed of metal and arranged within the dome of the tank between the main outlet of the dome and the inner outlet of the central tube. This baffle is curved and faces with its concave side outwardly and toward the main outlet and the same is inclined toward the center of the apparatus and secured at its horizontally opposite edges to the inner side of the dome while its upper

and lower edges are spaced therefrom to form upper and lower passages 26, 27 through which the liquid passes from the outer chamber to the outlet of the apparatus. 5 The upper passage 26 is comparatively large while the lower passage is comparatively small.

As the apparatus is inverted the liquid from the outer chamber is deflected by the 10 inclined baffle inwardly toward the liquid issuing from the outlet of the inner chamber so that they become mixed immediately and then this mixture of the two liquids constituting the extinguishing solution escapes 15 through the upper large passage above the baffle and thence through the main outlet and to the hose and its nozzle by which the attendant plays the mixed extinguishing fluid on the flames. This mixing operation 20 is so rapid that any fluid of the outer chamber passing through the small lower passage below the baffle is negligible and whatever may pass is promptly mixed with the main body 25 of mixed fluids which quickly reaches the concave side of the baffle after inverting the apparatus.

By thus directing the liquid of the outer chamber toward the outlet of the inner chamber before any liquid can escape to the exterior of the apparatus, proper mixing of the different kinds of liquids is assured and a marked increase in the efficiency of the apparatus is obtained.

When the apparatus is restored to its upper right position any liquid which may be present on the outer or concave side of the baffle drains from the same through the lower small intermediate passage 27 into the outer chamber of the tank and thereby prevent 40 any mixed solution from being trapped in the baffle and corroding the same.

Aside from being very efficient these baffle means are very simple in construction and do not materially increase the cost of the apparatus.

I claim as my invention:—

1. A fire extinguisher comprising a tank forming an outer chamber adapted to contain one liquid of an extinguishing fluid and having an outlet at its upper end, a tube arranged within the tank and forming an inner chamber adapted to contain another liquid of an extinguishing fluid and provided at its upper end with an outlet, a screen arranged over the inner side of the outlet of the tank, and a baffle arranged within the tank between said screen and the outlet of said inner chamber, and having its horizontally opposite ends connected with the adjacent wall of the outer chamber and separated at its upper and lower ends from the adjacent wall of the outer chamber by upper and lower passages.

2. A fire extinguisher comprising a tank 65 forming an outer chamber adapted to contain

one liquid of an extinguishing fluid and having an outlet at its upper end, a tube arranged within the tank and forming an inner chamber adapted to contain another liquid of an extinguishing fluid and provided at its upper end with an outlet, and an imperforate baffle arranged between said outlets and shaped and positioned to cause the liquids to flow in such manner that they mix upon inverting the apparatus before any of the liquid escapes from the outlet of the tank said baffle having its side edges connected with the inner surface of said tank and its upper and lower edges disconnected therefrom to form upper and lower passages for said liquids. 70

3. A fire extinguisher comprising a tank forming an outer chamber for the reception of one liquid of a fire extinguishing fluid and having a cylindrical body and a semi-spherical dome containing a main outlet for said extinguishing fluid upon inverting the apparatus, a tube arranged within the tank and forming an inner chamber for containing another liquid of the fire extinguishing fluid and having an inner outlet adjacent to said main outlet, and an imperforate baffle which is interposed between said inner and main outlets and which is inclined and curved horizontally so that its concave side faces outwardly and is secured at its horizontally opposite edges to the dome of the tank while its upper and lower edges are spaced from the dome to form upper and lower passages for the extinguishing fluid. 75

4. A fire extinguisher comprising a tank forming an outer chamber for the reception of one liquid of a fire extinguishing fluid and having a cylindrical body and a semi-spherical dome containing a main outlet for said extinguishing fluid upon inverting the apparatus, a tube arranged within the tank and forming an inner chamber for containing another liquid of the fire extinguishing fluid and having an inner outlet adjacent to said main outlet, an imperforate baffle which is interposed between said inner and main outlets and which is inclined and curved horizontally so that its concave side faces outwardly and is secured at its horizontally opposite edges to the dome of the tank while its upper and lower edges are spaced from the dome to form upper and lower passages for the extinguishing fluid, and a semi-spherical screen arranged between the baffle and the dome and having its concave side facing outwardly and its edge secured to the dome. 100

5. A fire extinguisher comprising a tank forming an outer chamber for the reception of one liquid of a fire extinguishing fluid and having a cylindrical body and a semi-spherical dome containing a main outlet for said extinguishing fluid upon inverting the apparatus, a tube arranged within the tank and forming an inner chamber for containing another liquid of the fire extinguishing fluid 105

and having an inner outlet adjacent to said main outlet, and an imperforate baffle which is interposed between said inner and main outlets and which is inclined and curved horizontally so that its concave side faces outwardly and is secured at its horizontally opposite edges to the dome of the tank while its upper and lower edges are spaced from the dome to form upper and lower passages for the extinguishing fluid said upper passage being comparatively large and said lower passage being comparatively small.

10 In testimony whereof I hereby affix my signature.
